Primary Examiner — Catherine Ho

(57) **CLAIM**

The ornamental design for a magnetic panel holder, as shown and described.

DESCRIPTION

FIG. 1 is a perspective view of a magnetic panel holder showing the front, top, and right side of my new design; FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The claimed magnetic panel holder is used to hold panels easily, flexibly and firmly with its magnetic base on surfaces made of ferromagnetic material.
